FREDERICK J. VAN CISE AND WILLIAM C. VAN CISE, OF MAYVILLE,
NEW YORK.

MATTRESS-FRAME.

SPECIFICATION forming part of Letters Patent No. 763,442, dated June 28, 1904.

Application filed February 14, 1903. Serial No. 143,326. (No model.)

To all whom it may concern:

Be it known that we, FREDERICK J. VAN CISE and WILLIAM C. VAN CISE, citizens of the United States, and residents of Mayville, 5 in the county of Chautauqua and State of New York, have invented a new and useful Mattress-Frame, of which the following, taken in connection with the accompanying drawings, is a full, clear, and exact description.

10 The invention relates to frames for woven-wire mattresses; and the object of our improvement is to provide a light and rigid metallic frame which will not warp or torsion. This purpose is accomplished by making the 15 side and end rails of sheet metal, with flanges thereon and a corner-block which connects and locks the side and end rails by the use of one bolt at each corner in a manner herein-after described.

20 In the drawings, Figure 1 is a plan view of one end of a woven-wire mattress having our improvements. Fig. 2 is an end elevation of one corner of the mattress-frame, showing the construction of our side rail and corner-block. 25 Fig. 3 is an end elevation of a modification of our side rail and corner-bolt. Fig. 4 is a side elevation of a corner of our mattress-frame. Fig. 5 is a plan view of corner-block.

Similar numerals refer to corresponding 30 parts in the several views.

The numeral 1 is the fabric, which is usually made of woven wire. The frame is composed of a side rail 2, which is made of two pieces of sheet metal. The lower piece 3 is 35 made in a V shape, with a cylindrical lower side 4, which gives great strength to the bottom of the rail. The upper edges of piece 3 are turned outward in flanges 5. The cap-piece 8 extends straight across the upper part 40 of the V a little below the top and is shaped so as to correspond with the angle of the V, as at 7, and then turned out horizontally at each side and is turned down over flanges 5, thereby completing the two flanges 6 at the 45 upper corners of the rail.

It is apparent that the straight central part of cap-piece 8, in combination with the angles 7, forms a brace or lock which prevents the withdrawal of side flanges 5 from the turned

edges of the cap-piece 8. On account of this 50 brace it is usually only necessary to insert a rivet 9 at each end of flanges 6 to hold the parts in place and prevent torsion of the rail.

A modification of the cap-piece 8 is shown in Fig. 3 in the inner V 10, which would 55 serve a good purpose, but does not brace as squarely across the V-shaped under piece 3, or piece 8 may extend straight across the top of the rail, as shown at dotted line 11 in Fig. 3, and make a strong rail; but it cannot brace 60 and lock the corner, as hereinafter described, and therefore the form shown in Fig. 2 is preferred.

Our corner-block 12 is made on its lower side with rabbeted edges 13, which fit the 65 angles 7 of piece 8 and the tops 14 of the flanges 6. Block 12 is made of sufficient length that the tongue formed by the rabbeted edges may have a strong hold in the groove in the upper side of side rail 2. It is ex- 70 tended out beyond the end of the rail for some distance and rounded, as at 15, for convenience in drawing the end of the mattress along the floor—as, for instance, when the furniture-dealer draws the mattress from the rack 75 to show the same. Crosswise in the upper side of block 12 is the cut 16, whose use will be hereinafter explained. A hole 17 is provided in block 12 for a corner-bolt 19.

End rail 18 is made the same as the side 80 rail, with the exception that we usually insert a wooden core 23 through the entire length of the end rail 18 to give added strength and stiffness for clamping the fabric thereon. Rail 18 is placed upon its side upon the two 85 corner-blocks 12 at one end and with a flange 6 in crosscuts 16 in the two blocks. Cross-cut 16 is made with just sufficient width to receive flange 6 on the lower side of the end rails, and it is apparent that each end of the 90 end rail 18 will thus be held as in a mortise at right angles to the side rails 2, and that the two corner-blocks at each end of the frame will assist each other in locking the rail.

The entire corner is held in place by corner-bolt 19, which extends up through the end of side rail 2, through corner-block 12 and end rail 18, and it is obvious that when the corner 95
